(57) **CLAIM**

The ornamental design for a micropigmentation device, as shown and described.

DESCRIPTION

FIG. 1 is a perspective front view of a micropigmentation device;

FIG. 2 is a perspective back view thereof;

FIG. 3 is a left view thereof;

FIG. 4 is a right view thereof; and,

FIG. 5 is a reduced perspective back view thereof.

The broken lines showing portions of the micropigmentation device form no part of the claimed design.

1 Claim, 5 Drawing Sheets

FIG. 1

FIG. 2

FIG. 3

FIG. 4

FIG. 5
